RADIATOR TRANSPORTING TRUCK

Filed Oct. 20, 1924

Inventor
O. H. Schuh,

By *Clarence Atkinson*

Attorney

UNITED STATES PATENT OFFICE.

OTTO H. SCHUH, OF INDIANAPOLIS, INDIANA.

RADIATOR-TRANSPORTING TRUCK.

Application filed October 20, 1924. Serial No. 744,704.

To all whom it may concern:

Be it known that I, OTTO H. SCHUH, a citizen of the United States, residing at Indianapolis, in the county of Marion and State of Indiana, have invented certain new and useful Improvements in a Radiator-Transporting Truck, of which the following is a specification.

This invention relates to an improved transporting truck which has been especially designed for moving heating radiators of the steam and hot water type to facilitate handling thereof.

The novelty of the present device resides in one instance in the construction of an improved truck which has been especially designed to render it sturdy and exceedingly easy to move from place to place with its load.

A structural feature to be noted in the improved device is the means utilized for lifting a radiator off of the ground and supporting it in spaced relation above the same to permit it to be readily transported from place to place.

Briefly described, the improved device comprises a light weight, yet sturdy, well supported transporting truck equipped with a pair of hoisting and supporting devices to be engaged with the bottom of the radiator to permit it to be lifted up off the ground. Appropriate means is provided for maintaining the devices in a set position, an additional means is provided for maintaining the radiator upright on the hoisting means.

The structural features and advantages derived therefrom will become apparent from the following description and drawing.

In the accompanying drawing forming a part of this application and in which like numerals are employed to designate like parts throughout the same:

Figure 1 is a side elevation of a truck constructed in accordance with the present invention.

Figure 2 is an end elevation thereof, and

Figure 3 is an enlarged detail view of a portion of one of the lifting devices.

Referring to the drawing in detail, it will be seen that the improved truck preferably comprises a pair of inverted U-shaped end-frames 1 which are connected together by pairs of upper and lower angle irons 2.

Appropriate rubber tired ball bearing cast-

ers 3 are carried by the lower portions of the legs of said end frame. One pair of the casters is preferably of the stationary type, while the remaining pair comprises swiveled casters. Slidably mounted upon the upper angle irons are fulcrum blocks 4 of the construction more plainly seen in Figure 2. Pivotedly mounted adjacent one end to the fulcrum blocks are lifting levers 5. At their free ends the levers are provided with handles 6 of appropriate shape. Pivotedly connected to the opposite ends of the levers and depending therefrom are lifting rods 7. As shown better in Figure 3, the lower end of each rod extends slidably through a guide sleeve 8 carried by a block 9 slidably mounted on the lower angle iron. Swiveled upon the lower end of this rod and maintained in place by the head with which it is equipped, is a laterally extended bracket arm 10 having its free end curved longitudinally as indicated at 11 to conform to the bottom of the radiator with which it is adapted to be engaged. For cooperation with each handle 6, I have provided a collar 12 which is held in place on one of the legs of each end frame by the set screw or the like. This collar is equipped with a hook shaped keeper 13.

As before intimated, appropriate means is provided for maintaining the radiator upright while it is being transported. While this means could be of some other construction, it preferably comprises a cylindrical bar or its equivalent 14 mounted between the upper and lower angle irons on one side of the truck. A collar 15 is adjustably mounted upon this bar 14 and is held in adjusted position by a setscrew 16 with which it is equipped and the collar carries a laterally extending arm 17 provided at its free end with a hook 18 to fit over the top portion of the radiator.

In use, the handles 6 are disengaged from the keeper hooks 13 and the bracket arms 10 are lowered by swinging the levers 5 upwardly. The bracket arms 10 are then placed beneath the opposite ends of the bottom of the radiator as shown in Figure 2. The levers are then swung downwardly upon their pivots and the handles are reengaged with the keeper hooks, thus suspending the radiator in the hoisted state shown. The arm 17 is adjusted to permit the hook 18 to be engaged with the top of the radia-

tor to maintain it in an upright position. Now, the radiator can be moved from place to place on the easy rolling truck.

Having thus described the invention, 5 what I claim is:—

1. In a radiator supporting truck of the class described, a wheel supported truck, a fulcrum block adjustably mounted thereon, a lever pivotally mounted between its ends 10 on said block, a handle on one end of said lever, a keeper with which said handle is adapted to be engaged, a hoisting rod pivotally connected to the opposite end of the lever and depending therefrom, a second 15 block adjustably mounted upon said truck, said second named block being equipped with a guide through which said rod is slidably, and a laterally directed radiator engaging arm swivelly mounted upon the 20 lower end of said rod.

2. A radiator transporting truck having supporting casters, a fulcrum block slidably mounted upon said truck, a lever pivoted between its ends on said block, said 25 lever having a handle on one end, a relatively stationary keeper with which said handle is adapted to be engaged, a hoisting rod pivotally connected to the opposite end of the lever and depending therefrom, a second block mounted upon said truck and 30 provided with a guide through which said rod is adapted to slide, a laterally disposed radiator engaging bracket arm is swivelly mounted upon the lower end of said rod, and a laterally extending 35 adjustably mounted arm also carried by the truck and pro-

vided at its free end with a hook adapted to fit over the top of a radiator for supporting it in an upright position on said bracket arm.

3. In a radiator transporting device, a wheel supported truck embodying inverted U-shaped end frames connected together by horizontal vertically spaced rails, a fulcrum block slidably mounted upon each of the upper rails, levers pivoted between their ends on said fulcrum blocks, relatively stationary keepers carried by the end frame, the levers being adapted to be connected at the corresponding ends with said keepers, a vertically disposed hoisting rod pivotally connected to the opposite end of each lever and depending therefrom, additional blocks slidably mounted on the lower rails, said additional blocks being provided with guides through which said hoisting rods are slidably, laterally disposed radiator engaging bracket arms swivelly mounted upon the lower ends of said rods, a cylindrical member mounted between the rails on one side of the truck and disposed in a vertical position, a collar slidably mounted upon said member, means for maintaining the collar in various adjusted positions, a laterally extending arm, and a hook at the free end of said arm adapted to fit over the top portion of the radiator to maintain the same in vertical position.

In testimony whereof I affix my signature,

OTTO H. SCHUH.
